(57) **CLAIM**

The ornamental design for a shade panel portion, as shown and described.

DESCRIPTION

FIG. 1 is a perspective view of a shade panel portion according to my design.

FIG. 2 is a front elevation view of the shade panel portion shown in FIG. 1.

FIG. 3 is a rear elevation view of the shade panel portion shown in FIG. 1.

FIG. 4 is a left side elevation view of the shade panel portion shown in FIG. 1.

FIG. 5 is a right side elevation view of the shade panel portion shown in FIG. 1.

FIG. 6 is a top plan view of the shade panel portion shown in FIG. 1; and,

FIG. 7 is a bottom plan view of the shade panel portion shown in FIG. 1.

The dash lines in FIGS. 1-7 depict portions that form no part of the claimed design.
